TAPPING DEVICE FOR LIQUID-CONTAINING VESSELS

George Lamoureux, Worcester, Mass.

Application February 26, 1947, Serial No. 731,104

3 Claims. (Cl. 222—464)

1

The present invention relates to keg-tapping devices, and more particularly to that type of tapping device comprising a sleeve adapted to be applied to the tapping hole of a keg and containing a valve designed normally to seal the opening in the sleeve by which the fluid passes from the keg, together with a faucet member adapted to form a fluid-tight joint with and screwed into the sleeve and to draw off fluid from the keg; this arrangement being such that when the faucet member is inserted into and turned in one direction within the sleeve the valve is opened, and when the member is rotated in the other direction the valve is closed. Such sleeve and valve units are adapted to be applied to a liquid container and used therewith throughout the life of the container unless breakage requires the removal of such unit. On the other hand, the faucet member is adapted only to be applied to the sleeve for the actual tapping operation and does not usually accompany the container from place to place.

More particularly, the present tapping unit is adapted to be applied to a beer keg tapping hole which is located within the side wall of a keg, or to other similar container, adjacent the bottom portion thereof. Used in conjunction with this sleeve and valve unit is an air line which is adapted to be attached to the top portion of the keg thereby to place the contents of the keg under a continuous pressure to the end that the liquid contents thereof may be delivered to any desired location through the hereinabove noted faucet member. This air or pressure line may be secured to the keg, or any other like vessel, in a manner similar to that employed in securing the faucet member to the keg. However, the present invention is concerned only with the sleeve, valve, and faucet combination, and no detailed reference will be made to the well-known air or pressure line structure.

As thus generally described, the above noted keg-tapping system is old and well-known in the art. However, such prior systems had none serious drawback and that was that they did not function to clear the keg completely of its liquid contents. For example, it has been found that such systems would usually leave about 4½ quarts of liquid remaining in the keg after the completion of the tapping operation. By tipping the keg it could be cleared of an additional 2 quarts of liquid thus leaving 2½ quarts remaining in the keg for the reason that with the above type of tapping system it is mechanically impossible to locate the valve unit sufficiently

close to the bottom of the keg to clear the same completely. Therefore, it is the object of the present invention to provide a keg-tapping means which will be effective to clear a keg of substantially all of its liquid contents.

A further object of the present invention is to provide a relatively inexpensive but efficient means which may be applied to the existing type of tapping units whereby the latter may be made to function so efficiently that they will clear a keg of substantially all of its liquid contents.

With the above and other objects in view, as will hereinafter appear, the invention comprises the devices, combinations and arrangements of parts hereinafter set forth and illustrated in the accompanying drawings of a preferred embodiment of the invention, and the advantages attained thereby will be readily understood by those skilled in the art.

In the drawings:

Fig. 1 represents a perspective view of a beer keg having the present type of tapping device and air pressure line attached thereto.

Fig. 2 represents, on an enlarged scale, a longitudinal sectional view through the present valve and sleeve device and showing a portion of a keg unit in section.

Fig. 3 represents a vertical sectional view taken substantially along line 3—3 of Fig. 2.

Fig. 4 represents a right-hand end view of the device as disclosed in Fig. 2 and showing by means of dotted lines, the initial position of the adaptor or valve unit.

Fig. 5 represents a vertical sectional view taken substantially along line 5—5 of Fig. 2.

Fig. 6 represents a side view of a faucet member which is positioned as if the same were to be inserted into the sleeve and valve unit disclosed in Fig. 2.

Fig. 7 represents a right-hand end view of the faucet member disclosed in Fig. 6.

Referring particularly to Fig. 1, there is illustrated a keg 10 which has attached to its upper head portion 11 a usual type of hand-actuated valve unit 12 which in turn is connected to an air pressure line 13 by means of a flexible hose 14 and valve 15. Whenever the valves 12 and 15 are opened the air is delivered under pressure through the pipe 13 to the end that the liquid contents of the keg are placed under a continuous pressure. A tapping device including a faucet element 16 is attached to the lower portion of the side wall of the keg for the purpose of delivering the keg's contents to a hose

17 which, in turn, will conduct the fluids to any desired location.

Referring particularly to Fig. 2, there is illustrated a vertical sectional view through a portion of the side wall 18 and the bottom wall 19 of the keg in which is formed the usual tapping hole 20. This tapping hole 20 is defined by means of an inwardly projecting cylindrical wall member 21 the inner portion of which is provided with an annular rib 22 and the opposite end portion of which is threaded as at 23. This tapping hole is adapted to receive a hollow cylindrical sleeve member 24 which is provided with an annular head 25 having an outwardly projecting key 26. The key 26 is slidably received within a key slot 27 formed in the peripheral wall portion of the hole 20. Thus, the key 26 and key slot 27 function to prevent the turning of the sleeve 24 within the tapping hole 20. In order positively to secure the sleeve 24 within the tapping hole a locking ring 28 is screwed into the forward portion of the hole thereby to bear against the head portion 25 of the sleeve. A sealing gasket 29 is positioned between the rib 22 and the rear shoulder of the head 25 so that when the ring 28 is tightened against the head it will be effective to compress the gasket 29 to the end that no liquids may escape through the hole 20 about the outside of the sleeve 24.

The inner portion of the sleeve 24 is closed over by means of a back wall 30 which is provided with a pair of apertures or inlet ports 31 and 32 circumferentially spaced within the back wall and also a centrally disposed aperture 33 which is adapted to receive a stud or key member 34. This stud member 34 is provided with an annular disk 35 which abuts the inner face of the back wall 30, and projecting inwardly from the disk 35 is a diamond shaped key head 36. As thus described, the present sleeve and stud combination is broadly old and in the past such studs had mounted on their distal ends a valve unit which was effective in one position to block off completely the apertures 31 and 32 from the inner portion of the keg thereby to prevent the fluid contents thereof from issuing through the central portion of the sleeve 24. Furthermore, whenever a faucet member (which will be described hereinafter) was inserted into the sleeve and in engagement with the key head 36 the faucet could be turned for the purpose of turning the stud 34 to the end that the valve unit would be rotated so as to expose the apertures 31 and 32 for the purpose of permitting the liquid to flow out of the tapping hole through the sleeve member 24.

Those skilled in the art will readily appreciate that since, by necessity, the apertures 31 and 32 are located a substantial distance above the keg bottom 19 it would be impossible to clear the keg completely by forcing the liquid contents thereof through these apertures by merely exposing the same to the liquid and applying air pressure to the inner portion of the keg. Therefore, the present invention contemplates the provision of a novel valve unit which comprises a substantially circular body member 37 which is mounted upon the distal end of the stud 34. The stud may be provided with a key 38 which will mate with a keyway 39 provided within a central bore 40 of the member 37. Thus, the member 37 is prevented from turning relative to the stud 34. In order to prevent endwise movements of the stud 34 the extreme-end portion thereof is threaded as at 41 thereby to receive a pair of

lock nuts 42, 42 which will be effective to draw the member 37 towards the rear wall 30 of the sleeve 24. Positioned between the back wall 30 of the sleeve 24 and the member 37 is a cylindrical gasket 43 which is secured upon the face 44 of the member 37 by means of an appropriate adhesive. Thus, whenever the member 37 is turned the gasket 43 will move in synchronism therewith. Positioned between the nuts 42 and the member 37 is a washer 45 which is adapted to bear against a shoulder portion 46 of the member 37 and also to bear against a gasket member 47 which is positioned within a recess 48 formed within the member 37 and about the stud 34. From the above it will be understood that the gaskets 43 and 47 will be effective to prevent any leakage of the fluid into the central portion of the sleeve 24 about the stud 34. Referring particularly to Figs. 2, 4, and 5, the valve member 37 has projecting outwardly from its central hub portion 49 a hollow tube or conduit member 50. This tube or conduit member 50 is provided with a bore 51 which opens through the face of the valve member 44 thereby to register with the inlet port 32 provided in the back wall 30 of the sleeve 24. An aperture 52 is provided in the gasket 43 so that it will register with the aperture 32 and bore 51 thereby to permit free passage of the fluids through the bore 51 and into the sleeve 24 whenever the bore is placed in register with the aperture 32. Fig. 2 discloses the valve unit disposed so that it may have its bore 51 in register with the aperture 32 and thus function to clear the keg of its liquid contents whenever the liquid is placed under air pressure. It is to be particularly noted that the tube element 50 projects beyond the confines of the sleeve 24 and depends downwardly from the valve member 37 to a point immediately adjacent the bottom portion of the keg 19. From this it will be understood that the present valve unit will adapt the above described tapping unit so that the latter may be effective to clear substantially all of the liquid contents from the keg. Fig. 4 illustrates the valve unit, in solid lines, as positioned for clearing the keg and, in dotted lines, it is shown in its closed or initial position so that the apertures 31 and 32 will be completely blocked off; it being understood that whenever the present valve unit 37 is applied to such a tapping unit the aperture 31 is rendered ineffective at all times.

Referring particularly to Figs. 1, 2, 6 and 7, the present valve unit is adapted to be actuated by means of the usual faucet or draw-off member generally designated by the numeral 16. It will be sufficient to say that this faucet member includes the usual cock 53 and spout 54 which are applied to a hollow draw-off tube 55 the free end portion of which is provided with a head member 56 about the periphery of which is formed a pair of circumferentially spaced coupling means or lugs 57, 58. Projecting outwardly from the head member 56 is a usual key portion 59 having a diamond shaped opening 60 formed therein for the purpose of receiving the key member 36 of the stud 34. Disposed about the periphery of the member 59 are a plurality of apertures 61, 61 which place a bore 62 of the draw-off tube in communication with the outside. In operation, the faucet member 16 is adapted to be inserted within the forward portion of the sleeve 24 so that the lugs 57 and 58 will each engage a respective one of the L-shaped slots 63 and 64 after which the faucet

is turned in a clockwise direction thereby to lock the same within the sleeve, all in the usual manner. Over the member 59 there is placed a gasket 65 which is adapted to be positioned between the head member 56 of the faucet and an annular rib member 66 of the sleeve unit to the end that no liquid may escape out through the tapping hole 20 about the head member 56 of the faucet. It is to be understood that whenever the faucet member is initially placed within the sleeve 24 the diamond shaped opening 60 will receive the similarly shaped key 36 and thus when the faucet is turned in a clockwise direction in order to lock the same within the sleeve, the valve unit will be shifted from its closed position to its open position. Thus, by the same token, when the faucet member is removed from the sleeve it will be necessary to turn the same in a counterclockwise direction thereby simultaneously closing the valve and unlocking the lugs 57 and 58 from the L-shaped grooves or channels 63 and 64. Fig. 4 illustrates, in dotted lines, the initial position taken by the tube 50 of the valve unit. This initial position of the valve unit is its closed position and it will be shifted in the direction of the arrow to its open position whenever the faucet member is turned to its locked position.

From the above it is to be understood that the present valve unit 37 comprises a means which may be economically manufactured and which at the same time may be applied readily to the usual existing type of keg-tapping unit to the end that the latter may be rendered effective for clearing a keg of substantially all of its liquid contents thereby saving substantial sums of money for the user of such units.

I claim:

1. In a device for sealing and opening the tapping hole of a liquid container, said device having a sleeve adapted to be applied to the tapping hole of the container, a key rotatably mounted within and axially of said sleeve, coupling means provided within said sleeve, a draw-off member having complementary coupling means and adapted to be rotated in one direction for locking and in an opposite direction for unlocking the same to and from said sleeve, and means carried by said draw-off member for engaging said key so as to rotate the same in synchronism with said draw-off member; the combination which consists in the provision of a valve member mounted upon and turnable with said key from a closed to an open position as said draw-off member is rotated from its unlocked to its locked position, said valve member comprising, a body portion secured upon said key, and a conduit member, in communication with said sleeve in the open position of said valve member, and projecting from said body portion and outwardly relative to said sleeve so as to project a substantial distance beyond the confines of said sleeve.

2. In a device for sealing and opening the tapping hole of a liquid container, said device having a sleeve adapted to be applied to the tapping hole of the container, a back wall closing over the inner end portion of said sleeve and having an inlet port therein, a key rotatably mounted within said back wall and axially of said sleeve, coupling means provided within said sleeve, a draw-off member having complementary coupling means and adapted to be rotated in one direction for locking and in an opposite direction for unlocking the same to and from said sleeve, and means carried by said draw-off member for engaging said key so as to rotate the same in synchronism with said draw-off member; the combination which consists in the provision of a valve member, said valve member comprising, a body portion secured upon and turnable with said key and disposed adjacent the outside face of said back wall, and an elongated hollow tube projecting from said body portion and radially of said sleeve so as to project a substantial distance beyond the confines of said sleeve, said hollow tube being disposed in communication with said sleeve through said inlet port when said draw-off member is in its locked position.

3. The combination with a liquid container having a tapping hole disposed in a side wall adjacent the bottom portion thereof, of a sleeve adapted to be applied to said tapping hole, a key rotatably mounted within and axially of said sleeve, coupling means provided within said sleeve, a draw-off member having complementary coupling means and adapted to be rotated in one direction for locking and in an opposite direction for unlocking the same to and from said sleeve, means carried by said draw-off member for engaging said key so as to rotate the same in synchronism with said draw-off member; a valve member mounted upon and turnable with said key from a closed to an open position as said draw-off member is rotated from its unlocked to its locked position, and an elongated hollow tube projecting from said valve and radially of said sleeve so as to project a substantial distance beyond the confines of said sleeve, said hollow tube being in communication with said sleeve, and having its free end portion disposed immediately adjacent the bottom portion of said container whenever said valve is in its open position.

GEORGE LAMOUREUX.
